CLAIM

The ornamental design for an autonomous vehicle, as shown and described.

DESCRIPTION

FIG. 1 is a front perspective view of a first embodiment of an autonomous vehicle with right side compartment doors;

FIG. 2 is a rear perspective view of the autonomous vehicle of FIG. 1;

FIG. 3 is a front view of the autonomous vehicle of FIG. 1; FIG. 4 is a rear view of the autonomous vehicle of FIG. 1; FIG. 5 is a first side view of the autonomous vehicle of FIG. 1;

FIG. 6 is a second side view of autonomous vehicle of FIG. 1;

FIG. 7 is a top view of the autonomous vehicle of FIG. 1; FIG. 8 is a bottom view of the autonomous vehicle of FIG. 1;

FIG. 9 is a rear perspective view of the autonomous vehicle, similar to FIG. 2, with right side compartment doors open; FIG. 10 is a front perspective view of a second embodiment of an autonomous vehicle with right side compartment doors;

FIG. 11 is a rear perspective view of the autonomous vehicle of FIG. 10;

FIG. 12 is a front view of the autonomous vehicle of FIG. 10;

FIG. 13 is a rear view of the autonomous vehicle of FIG. 10; FIG. 14 is a first side view of the autonomous vehicle of FIG. 10;

FIG. 15 is a second side view of autonomous vehicle of FIG. 10;

FIG. 16 is a top view of the autonomous vehicle of FIG. 10; FIG. 17 is a bottom view of the autonomous vehicle of FIG. 10;

FIG. 18 is a rear perspective view of the autonomous vehicle, similar to FIG. 11, with right side compartment doors open;

FIG. 19 is a front perspective view of a third embodiment of an autonomous vehicle with left side compartment doors; FIG. 20 is a rear perspective view of the autonomous vehicle of FIG. 19;

FIG. 21 is a front view of the autonomous vehicle of FIG. 19;

FIG. 22 is a rear view of the autonomous vehicle of FIG. 19; FIG. 23 is a first side view of the autonomous vehicle of FIG. 19;

FIG. 24 is a second side view of autonomous vehicle of FIG. 19;

FIG. 25 is a top view of the autonomous vehicle of FIG. 19; FIG. 26 is a bottom view of the autonomous vehicle of FIG. 19;

FIG. 27 is a rear perspective view of the autonomous vehicle, similar to FIG. 20, with left side compartment doors open;

FIG. 28 is a front perspective view of a fourth embodiment of an autonomous vehicle with left side compartment doors; FIG. 29 is a rear perspective view of the autonomous vehicle of FIG. 28;

FIG. 30 is a front view of the autonomous vehicle of FIG. 28;

FIG. 31 is a rear view of the autonomous vehicle of FIG. 28; FIG. 32 is a first side view of the autonomous vehicle of FIG. 28;

FIG. 33 is a second side view of autonomous vehicle of FIG. 28;

FIG. 34 is a top view of the autonomous vehicle of FIG. 28; FIG. 35 is a bottom view of the autonomous vehicle of FIG. 28; and,

FIG. 36 is a rear perspective view of the autonomous vehicle, similar to FIG. 29, with left side compartment doors open.

The broken lines illustrate portions of the autonomous vehicle that form no part of the claimed design.
